(57) **CLAIM**

The ornamental design for a welding helmet, as shown and described.

DESCRIPTION

FIG. 1 is a top, front and right side perspective view of a welding helmet, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view thereof, the cheater lens shown in a detached state;

FIG. 10 is an enlarged view of encircled portion labeled, “10,” in FIG. 1;

FIG. 11 is an enlarged view of encircled portion labeled, “11,” in FIG. 1;

FIG. 12 is an enlarged view of encircled portion labeled, “12,” in FIG. 2;

FIG. 13 is an enlarged view of encircled portion labeled, “13,” in FIG. 2;

FIG. 14 is an enlarged view of encircled portion labeled, “14,” in FIG. 2; and,

FIG. 15 is an enlarged view of encircled portion labeled, “15,” in FIG. 2.

The evenly dashed broken lines illustrate features of the welding helmet that form no part of the claimed design. The dot-dash broken lines define the boundaries of the enlarged view of FIGS. 10-15 in FIGS. 1,2, and 10-15 and form no part of the claimed design.
